UNITED STATES PATENT OFFICE.

ALLEN T. LOKEY, OF MEMPHIS, TEXAS.

COTTON-BOLL-CLEANING MACHINE.

1,351,858.

Specification of Letters Patent. Patented Sept. 7, 1920.

Application filed May 14, 1919. Serial No. 296,973.

To all whom it may concern:

Be it known that I, ALLEN T. LOKEY, a citizen of the United States, residing at Memphis, in the county of Hall and State of Texas, have invented certain new and useful Improvements in Cotton-Boll-Cleaning Machines, of which the following is a specification, reference being had to the accompanying drawings.

10 This invention relates to an improved cotton boll cleaning or ginning machine, and one of the objects of the invention is the provision of an apparatus of this kind for efficiently breaking the cotton bolls and 15 thoroughly separating the motes and dirt from the cotton.

A further object of the invention is to provide an apparatus which is very compact, simple and practical in construction, and 20 yet constructed whereby the cotton during its passage through the machine will receive a plurality of cleaning processes, so that all the motes and dirt may be removed from the cotton.

25 A further object of the invention is the provision of a machine of this kind including duplicate mechanisms one super-imposed with relation to the other and being so coupled that the cotton bolls after passing 30 through the super-imposed mechanism may be transferred to the other mechanism, thereby giving the cotton bolls a double cleaning, separating the motes and dirt from the cotton, during each cleaning process, dis- 35 charging the dirt and motes from both cleaning processes through a single discharge chute and delivering the cotton, when cleaned, through a single outlet chute.

40 While the design and construction at present illustrated and set forth is deemed preferable, it is obvious that as a result of a reduction of the invention to a more practical form for commercial purposes, the invention may be susceptible to changes, and 45 the right to these changes is claimed, provided they are comprehended within the scope of what is claimed.

The invention comprises further features and combination of parts, as will be herein- 50 after set forth, shown in the drawings and claimed.

In the drawings:

Figure 1 is a vertical sectional view

through the cotton boll cleaning or ginning machine.

55

Fig. 2 is a vertical sectional view on line 2—2 of Fig. 1.

Fig. 3 is a sectional view on line 3—3 of

Fig. 1.

Fig. 4 is a sectional view on line 4—4 of Fig. 1.

60

Fig. 5 is a view of one end of the machine or apparatus.

65

Fig. 6 is a view of the opposite end of the machine.

Referring more especially to the drawings, 1 designates a casing provided with a hopper 2, there being a passage 3 leading from the hopper into the casing. A plate, or board or other suitable member 4 is hinged 70 at 5, there being a rod 6 provided with a handle 7 and connected to the board or plate, for adjusting the same, in order to restrict the passage 3, whereby the cotton bolls may be governed in their passage through the 75 space 3.

It is to be observed that the casing or housing of the machine is divided into compartments 8 and 9, the former being super-imposed with relation to the latter. These 80 compartments are formed, owing to the provision of a partition. This partition comprises longitudinal bars 10, 11 and 12, which support the sheet metal concave 13, and the combined concave and chute wall 85 14. The chute wall 14 connects to a vertical wall 15, between which and one wall of the casing a passage 16 is provided, through which the dirt and motes pass.

Arranged in the casing are supporting 90 bars 17 and 18, the bar 17 being fixed at the inner face of one wall of the casing, while the bar 18 is positioned a little below the bar 17, in between the bar 17 and the bar 11. It is to be noted that a coarse concave 95 screen member 19 is connected to and supported upon the bars 17 and 18, while a coarse concave screen 20 is connected to and supported by the bars 11 and 18, for the purpose of screening the cotton, in fact separating the motes and dirt from the cotton.

Also arranged in the casing are bars 21 and 22. The bottom of the casing is provided with an outlet opening 23, through which a discharge conduit 24 is connected. 105 A combined sheet metal concave and sheet

plate 25 is connected to the bar 22 and has its inclined portion 26 extending downwardly to the discharge opening 23. A sheet metal concave 27 is supported on the 5 bars 21 and 22.

Fixed to the inner face of the plate or wall 15 is a bar 28, and 29 denotes a bar, which is disposed a short distance below the bar 28, and spaced between bar 28 and the 10 bar 22. A fine concave screen 30 is supported upon the bars 28 and 29, and a second concave screen of fine mesh 31 is supported upon the bars 22 and 29. Mounted in the super-imposed compartment is a screw conveyer 32. This conveyer is spaced slightly from the concave screen 19, and concentric therewith.

Journalized in the super-imposed compartment and concentric with the coarse concave 20 screen 20 is a spiked cylinder 33, the spikes 34 of which are arranged at spaced intervals, and act to actuate and cause the dirt and motes to pass through the screen concave, so that the dirt and motes will pass out 25 through the passage 16, after feeding down the inclined chute plate 14.

Also journalized in the super-imposed compartment is a cylinder 35, provided with longitudinally extending angle irons 36. This cylinder 35 is super-imposed and offset 30 with relation to the conveyer.

A shaft 37 is mounted in bearings of the casing, and mounted on the shaft to rotate therewith are circular saws 38, which are 35 held at spaced intervals by the members 39. A cylinder brush 40 is also journalized in the super-imposed compartment, and positioned in such wise with relation to the teeth of the circular saws, as to brush or 40 take the cotton from the saws, and deliver it into the chute 41, which is supported upon the bar 10, and extends through one wall of the casing, as at 42. This chute 41 communicates with a chute 43, which in 45 turn communicates with the chute 44. The chute or passage 16 communicates with a space 45, there being an inclined chute board or plate 46, so positioned as to carry the motes and the like to the discharge conduit 50 24. Journalized in the space 45 in a position above and relatively to the opening 23 is a conveyer 47. A conveyer 48 is journalized in the compartment 9, concentric with the screen concave 30.

55 Positioned in the compartment 9 and concentric with the screen concave 31 is a cylinder 49, provided with spikes 50 arranged at spaced intervals. Also mounted in bearings in the casing and positioned through 60 the compartment 9 is a shaft 51, which carries a plurality of spaced circular saws 52, the members 53 holding the saws spaced. These circular saws are positioned relatively to the conveyer and spiked cylinder, 65 so as to gather the cotton from the bur or

boll, the spikes of the cylinder assisting greatly in transferring the cotton to the saws.

Journalized in the compartment 9 is a cylinder 54, on which at spaced intervals 70 are angle irons 55, which are similar to the angle irons 36. This cylinder 54 is positioned above the conveyer 48 and the circular saws 52, in a position substantially in a plane between the conveyer and the circular saws 52.

Also journalized in the compartment 9 is a brush cylinder 56, which is similar to the brush cylinder 40, and is positioned so that the bristles will act to take the cotton from 80 the saws and deliver it through the chute 44.

Arranged in the casing is a bar 57, and depending downwardly from the bar 57 and downwardly from the inner face of the top wall of the casing are deflectors 58 and 85 59, which act to keep the greater part of the refuse from being conveyed by the saws to positions relative to the brush cylinders. These deflectors also prevent an excessive quantity of cotton being carried to positions relative to the brush cylinders, so that a certain amount of cotton may be brushed or taken from the saws, thereby preventing 90 crowding and injury to the bristles of the brushes.

The various cylinders, conveyers and saws are operated in the directions as indicated by the arrows.

Hinged to the bar 12 as at 60 is a plate or board 61, to which a member 62 is connected. This member 62 has a handle 63, and by grasping the handle the member 62 may be operated to regulate the plate or board 61. It is to be noted that the members or rods 6 and 62 are threaded through 105 the nut plates 64, and the inner ends of the rods or members 6 and 62 are connected to the plates or boards 4 and 61 by means of any suitable swivel joint as shown at 65. The lower edges of the plates or boards 4 110 and 61 are provided with laterally extending flanges 66, which extend toward the angle irons 36 and 55 of the cylinders 35 and 54. It is to be noted that by manipulating the rods 6 and 62, the plates or boards 4 and 115 61 may be adjusted so as to position the angular flanges 66 relatively to the angle irons of the cylinders 35 and 54. These flanges act to deflect the burs or bolls back toward and in coöperation with the conveyers 32 and 48. The angle irons on the cylinders 35 and 54 also act to deflect the burs or bolls back toward and in coöperation with the conveyers.

As heretofore stated, the various cylinders, conveyers, and the circular saws are rotated in the directions as indicated by the arrows, owing to the belting connections as will be hereinafter set forth.

It will be noted that this particular ma- 130

chine enables the burs or bolls to have a considerable travel, in order to be cleaned of the cotton. The bolls or burs are first thoroughly broken up by means of a machine (not shown), and are discharged into the hopper 2 of the separator. The bolls or burs are carried adjacent the teeth of the circular saws of the saw cylinder 38 by means of the left hand conveyer 32, the 10 teeth of the circular saws acting to pick up the cotton, and this act of picking up the cotton tends to also pick up the burs or bolls, or that is a part of the burs; therefore the cylinder 35 with its angle irons 36 are provided for beating or knocking the burs or bolls back toward and in coöperation with the conveyer 32. The cotton picked from the burs or bolls are carried by the teeth of the cylinders, and by means of the brush 15 cylinders, the cotton is picked or brushed from the teeth of the circular saws and delivered through the chute 41. The dirt and motes are screened by the screening concaves 19 and 20. The spikes of the cylinder 20 33 will act to agitate the motes and dirt so that they will easily pass through the screen concave 20, and also the spikes of the cylinder 33 will help to deliver the cotton to the saws. Such burs or bolls that are not thoroughly cleaned or separated, and are beat back toward and in coöperation with the conveyer 32 will travel along the conveyer 32, from one end of the machine to the other, and pass through a chute 67, toward and 25 in coöperation with the lower conveyer 48, where the boll or bur will pass through the same process, as previously set forth, in connection with the mechanism of the superimposed compartment, it being apparent 30 that the motes and dirt that are removed from the cotton by means of this second cleaning and separating process, will pass through the opening 23 and through the conduit 24, together with the dirt and motes 35 that may pass through the chute or passage 40 6. Also the cotton that is removed from the bur or particles thereof by means of this second separating process, will also be conveyed to and discharged through the chute 44, together with the cotton that passes 45 through the passage chute 43.

On one end of the shaft of the conveyer 48 a pulley 70 is mounted, to which any suitable bar (not shown) may be geared by 50 means of the belt 71. Also movable with the shaft of the conveyer 48 is a second pulley 72, which, by means of the belt 73, is geared or connected to the pulley 74, which is fast on the shaft of the conveyer 55 32. Also fast upon the shaft of the conveyer 32 is a gear 75, which meshes with a gear 76 on the shaft of the cylinder 35. On one end of the shaft of the cylinder 35 a pulley 77 is fixed, which has a belt 78 engaging about it. This belt 78 is in turn

passed about a pulley 79 on one end of the shaft 37, thereby transmitting power thereto. On the other end of the shaft 37 a gear 80 is fixed, which meshes with the gear 81, thereby transmitting power to the brush 70 cylinder. It will be noted that the gear 75 meshes with a gear 82, which is fixed to and rotatable with the shaft of the cylinder 33. Fixed on one end of the shaft of the cylinder 33 is a pulley 83 having a belt 84 75 passing about it. This belt 84 in turn passes about a pulley 85 on the shaft of the cylinder 54. A pulley 86 is fixed on the shaft of the cylinder 54, and engaging with the pulley 86 is a belt 87, which in turn engages a pulley 88 on the shaft 51 which carries the saws 52. A second pulley 89 is fixed to one end of the shaft 51 which carries the saws 52, there being a belt 90 engaging the same. This belt 90 engages 85 about the pulley 91 on the shaft of the cylinder 49, and since power is transmitted to the gears 75 and 82 to the cylinders 54 and the saw carrying shaft 51 through the medium of the belts 84 and 87, power is 90 transmitted to the cylinder 49 by means of the belt 90. The shafts of the cylinders 49 and the conveyer 47 by means of the gears 92 and 93, which are respectively mounted on the shafts of the cylinder 49 and the 95 conveyer 47, hence transmitting power to the conveyer 47. Gears 94 and 95 meshing with each other are mounted respectively on the shafts 51 and 96 of the saws 52 and the brush cylinder 56, whereby the brush cylinder 100 may be rotated in an opposite direction to the saws 52. From the foregoing gearing, it will be seen how power is transmitted to the various parts of the separator, so as 105 to rotate them in their proper directions to separate the cotton from the dirt and motes.

The invention having been set forth, what is claimed as new and useful is:

1. In a cotton cleaning machine, the combination with a casing having a boll chamber, of a cotton cleaning mechanism in said chamber comprising a conveying screw and cotton gathering saws operative in parallel planes on an axis parallel with the screw, a 110 knocker roll offset above and between the screw and the saws and provided with longitudinally extending spaced flanges adapted to knock the bolls back upon the feed screw, and a hinged combined deflector and guard 120 plate adjustable to approximate the longitudinal edges of the knocker flanges of the knocker roll to assist in knocking the bolls back toward and upon the conveyer.

2. In a cotton cleaning machine, the combination with a casing provided with a cotton cleaning chamber having a screen concave in its bottom, of a picker roll operable concentric with the concave for forcing or feeding the trash through the concave, a con- 130

- 4
- veyer screw for feeding the cotton bolls into the chamber and upon the picker rolls, cotton gathering saws operable in parallel planes and upon an axis parallel with the feed screw, of a knocker roll offset above and between the saws and the feed screw having knocker flanges extending longitudinally thereof, a combined guard and deflector having a right angle flange extending in a horizontal plane toward and in a direction of the axis of the knocker roll and adapted to approximate the longitudinal edges of the knocker flanges.
3. In a cotton cleaning machine, the combination with a casing provided with a cotton cleaning chamber having a screen concave in its bottom, of a picker roll operable concentric with the concave for forcing or feeding the trash through the concave, a conveyer screw for feeding the cotton bolls into the chamber and upon the picker rolls, cotton gathering saws operable in parallel planes and upon an axis parallel with the feed screw, of a knocker roll offset above and between the saws and the feed screw having knocker flanges extending longitudinally thereof, a combined guard and deflector having a right angle flange extending in a horizontal plane toward and in a direction of the axis of the knocker roll and adapted to approximate the longitudinal edges of the knocker flanges, and means for adjusting the combined guard and deflector whereby its flange may be moved toward and from the knocker flanges.
4. In a cotton cleaning machine, the combination with a casing having a cotton cleaning chamber, of a cotton bolling mechanism in said chamber, said casing having a hopper communicating with said chamber to feed the bolls toward said mechanism, a knocker roll below and to one side of the hopper provided with longitudinally extending radial knocker flanges, a combined guard and deflector pivotally suspended from one side 45 of the hopper adapted to approximate the longitudinal edges of said knocker flanges for knocking the bolls back toward the bolling mechanism, and means for adjusting said combined deflector and guard. 50
5. In a cotton cleaning machine, the combination with a casing provided with a cleaning chamber, of a bolling mechanism in said chamber, said casing having a hopper communicating with said chamber, a knocker roll above the bolling mechanism and between operating members thereof, boll knockers angular in cross section arranged longitudinally of the knocker cylinder and extending radially, a combined 55 guard and deflector pivotally suspended from the top of the casing and having a longitudinal knocker flange at its lower end disposed in a horizontal plane toward and in parallelism with the axis of the knocker roll to assist in knocking the bolls back toward and upon the bolling mechanism, and an element threaded in the wall of the casing and being swivelly connected to said combined guard and shield for adjusting the 60 same whereby the flange of the guard may approximate the longitudinal edges of the knockers on the knocker roll. 65
- In testimony whereof I hereunto affix my signature in the presence of two witnesses. 70
